UNITED STATES PATENT OFFICE.

HENRY R. STICKNEY, OF PORTLAND, MAINE.

CAN-FILLING MACHINE.

SPECIFICATION forming part of Letters Patent No. 693,921, dated February 25, 1902.

Application filed January 28, 1901. Serial No. 44,957. (No model.)

To all whom it may concern:

Be it known that I, HENRY R. STICKNEY, a citizen of the United States of America, and a resident of Portland, Cumberland county, 5 State of Maine, have invented certain new and useful Improvements in Can-Filling Machines, of which the following is a specification.

My invention relates to a machine for filling cans; and it is particularly designed for filling cans with viscous material like condensed milk.

The most important object of the invention is to construct such a machine which will 10 positively and quickly cut off the vertical stream of condensed milk when the can is full, or nearly so, the material being of such character that it acts very slowly when allowed to separate by its own weight. Hitherto this has generally been attempted by 15 means of various kinds of mechanical cut-offs; but it has been found by experience that anything of this kind which comes in contact with the stream of condensed milk as 20 it falls into the can soon becomes clogged with an accumulation of the viscous material, which sticks to it each time the stream is cut off and gradually accumulates until it stops the successful operations of the machine.

I remedy the above difficulties by suddenly retracting the upper portion of the vertical column of condensed milk as it comes from the filling-nozzle at the moment when the can is about full; and my invention resides 30 generally in the mechanical means by which I accomplish this—namely, a check-valve interposed between the filling-nozzle and the outlet-port of the cylinder which, before closing on the return of the plunger, allows the 35 stream of milk to be suddenly drawn back for a limited distance, thus parting the stream, drawing the upper portion back into the filling-nozzle and allowing the lower portion to fall into the can.

The invention further consists of a special 40 construction of the plunger by which its stroke may be accurately regulated while the machine is in operation and also means for easily changing the machine to adapt it to 45 different sizes of cans.

Another feature of my invention consists 50 of special means by which a single lever is

made to feed the cans and operate the plunger at the same time.

I illustrate my invention by means of the 55 accompanying drawings, which represent a double-cylinder machine constructed according to my invention.

In the drawings, Figure 1 is a side view with the filling mechanism proper showing in 60 section. Fig. 2 is a plan view of the rear ends of the plungers, showing the connecting parts. Fig. 3 is a front elevation of the upper portion of the machine with the vertical can-spouts omitted, and Fig. 4 is a detail 65 showing the adjustable connection of the cylinder with the frame of the machine.

A is the supply-hopper for containing the condensed milk, the lower end being secured 70 the casting A'.

P is the framework of the machine, which is designed to properly support the various parts described. As here shown, the casting A' is formed integral with and on the top of the cylinder B, which is fastened to the frame 75 of the machine by a bolt s', passing through a slot s in the flange b. An inlet-duct a leads forward from the outlet of the hopper to the inlet-port a', which is situated at the forward end of the cylinder. Within the cylinder is 80 a hollow plunger E, open at its rear end, and immediately below the inlet-port is an outlet-port a², situated, as here shown, in the axial center of the cylinder, and the valve-chamber a³, which is formed outside of the port, communicates with the vertical filling-nozzle d. The inlet and the outlet ports are provided 85 with check-valves b' and c', respectively, with the valve-stems b⁴ and c⁴ extending forward and inclosed in bonnets b³ and c³, the inner 90 ends of these bonnets screwing into the walls of the valve-chambers and forming the front sides thereof. Spiral springs b² and c² are provided to keep the check-valves normally closed. Means are provided for holding the 95 outlet check-valve c' open for a limited time after the plunger has started to return, so that the condensed milk in the nozzle d may be suddenly retracted for a short distance. For this purpose I provide an extension or 100 offset between the valve and the end of the plunger, here shown as a projection c on the inner end of the valve, against which the end of the plunger impinges to hold the valve

open. When the plunger starts to return, the projection *c* prevents the valve from immediately closing, and so causes the retraction of the liquid already spoken of. The plunger is 5 so constructed that its stroke may be accurately adjusted while the machine is running. As here shown, a spring case or cylinder *f* extends into the rear end of the plunger, and this spring-case is connected with a cross-head 10 *f'*, which runs in guides *h*. The forward end of the spring-case or that end within the plunger is closed, except for a central opening for the purpose hereinafter spoken of, and its rear end is open through the cross-head. The spring-case and the cross-head are connected by a spring connection which allows them to separate when the cross-head is drawn back and to come together as a solid plunger when the cross-head moves forward. 15 20 This is accomplished by means of a rod *e*, secured axially to the inner end of the plunger and extending backward through the central opening in the end of the spring-case and terminating at or near the open rear end of the 25 spring-case in a nut *e*³, and a spiral spring *e*² impinges against this nut and against the inner end of the spring-case.

An adjustable screw-stop *g* is provided in the cross-bar *g*², which unites the rear ends of 30 the guides *h*, and the screw-stop *g* is provided with a check-nut *g*'. On the rear end of the cylinder is a stuffing-box *e*', which makes a tight joint with the plunger. It will be seen that while the cross-head and the spring may 35 have the same length of stroke each time, the backward throw of the plunger may be varied by the position of the stop *g*, against which the end of the rod *e* strikes. If the stop *g* is screwed in so as to stop the plunger before 40 the cross-head has reached the rear of its stroke, the spring-case simply compresses the spring on the rod and then when the cross-head moves forward it impinges against the rear end of the plunger and pushes it in with 45 a positive motion.

It will be understood that most of the parts described are duplicated in a double-cylinder machine, such as is here shown, and the machine may be made with one or more cylinders placed side by side.

A reciprocating motion is imparted to the cross-head by the connecting-rods *j*, which are pivoted to the tops of the upright levers *J*, one on each side of the machine. These 55 levers *J* act at the same time to feed the cans and to operate the plungers. They are pivoted by their lower ends below the bed of the machine, and at a point below the upper end there is an offset *j*', which swings in under 60 the can-spout and forces the cans *i*' along between the guides *i*³ to a point beneath the filling-nozzle *d*.

The lower ends of the can-spouts are secured to a base *i*², connecting with the frame of 65 machine immediately over the guideways formed by the guides *i*³. The levers *J* are operated by connecting-rods *k*, pivoted to

crank-disks *k'* on gears *l*. Power is applied to a pulley *o* and transmitted through a pinion *m* to the gear *l*.

Sufficient has been said to show the operation of the machine, which is generally the same as most can-filling machines. The condensed milk is drawn in through the inlet-port when the plunger moves back, and when 70 the end of the rod *e* strikes the stop *g* the plunger stops. When the plunger moves forward, the material is forced out through the filling-nozzle into the can. The stream of condensed milk which extends from the lower 75 end of the filling-nozzle to the can at the end of the stroke is suddenly cut in two by the sudden retraction of the upper end of the stream by the backward movement of the plunger.

When smaller cans than the normal size are to be used, the bolts *s*', Fig. 4, are loosened and the cylinder is moved forward, the slot *s* permitting such movement.

It is evident that when the cylinder is moved 80 forward, the stroke of the cross-head remaining constant, the plunger will not reach the inner end of the cylinder. To adjust this difference in stroke, washers *w*, Fig. 2, are inserted between the outer end of the plunger 85 and the cross-head, thereby lengthening the plunger just enough to make its stroke complete.

I claim—

1. In a machine for filling cans with condensed milk the combination of a plunger and a cylinder therefor, an inlet-port and an outlet-port at the end of the cylinder, a filling-nozzle connecting with the outlet-port and adjacent thereto a check-valve for closing the outlet-port having a valve-stem in line with the plunger, a bonnet for containing the valve-stem and providing a bearing therefor, a spring for closing the valve and an inward-extending projection adapted to be struck by 100 the end of the plunger to hold the valve open.

2. In a machine for filling cans, the combination of a cylinder having an inlet and an outlet port, a hollow plunger for said cylinder open at its rear end, a spring-case extending 105 into said plunger from the rear end, a cross-head to which said spring-case is connected, a rod secured axially to the inner end of said plunger and extending through an opening in the spring-case, a spiral spring on said rod 110 impinging against the inner end of the spring-case and the outer end of the rod an adjustable stop for limiting the backward motion of said rod and means for reciprocating said cross-head to impart motion to the plunger.

3. In a machine for filling cans the combination of a cylinder adjustably mounted on the frame of the machine and having an inlet and an outlet port, a hollow plunger for 115 said cylinder open at its rear end, a spring-case extending into said plunger from the rear end, a cross-head to which said spring-case is connected, a rod secured axially to the inner end of said plunger and extending

through an opening in the spring-case and the outer end of the rod, an adjustable stop for limiting the backward motion of said rod, a washer adapted to be inserted between the 5 plunger and the spring-case to hold them apart and means for reciprocating said cross-head to reciprocate the plunger.

4. In a machine for filling cans the combination of a cylinder adjustably mounted on 10 the frame of the machine a plunger therefor inlet and outlet ducts, a filling-nozzle connected with the outlet-duct, a guideway for cans passing beneath said filling-nozzle, a

vertical can-spout above said guideway and adapted to drop cans therein, an upright lever fulcrumed below said guideway, an offset on said lever for feeding the cans through said guideway, a connecting-rod at the top of said lever for reciprocating said plunger and means for oscillating said lever.

Signed at Portland this 4th day of January, 1901.
